(57) **CLAIM**

The ornamental design for a tray attachment for a table, as shown and described.

DESCRIPTION

FIG. 1 is a perspective view of a tray attachment for a table of the present design;

FIG. 2 is a front elevational view of the tray attachment for a table of FIG. 1;

FIG. 3 is a rear elevational view of the tray attachment for a table of FIG. 1;

FIG. 4 is top plan view of the tray attachment for a table of FIG. 1;

FIG. 5 is a bottom plan view of the tray attachment for a table of FIG. 1;

FIG. 6 is a side elevational view of the tray attachment for a table taken from the right side of FIG. 1; and,

FIG. 7 is a side elevational view of the tray attachment for a table taken from the left side of FIG. 1.

Portions of FIGS. 1-7 that are shown as broken lines are for illustrative purposes only and form no part of the claimed design.
